poration of Ohio

Application July 5, 1941, Serial No. 401,138

12 Claims. (Cl. 274—13)

This invention relates to apparatus for the recording and reproduction of sound, and especially to apparatus of the type including a recorder adapted to form a record groove on a suitable blank, as well as a reproducer adapted for playing back the recorded material directly after recording.

Such apparatus is in general well known, one form being shown and described in an application filed in the name of Frank Rieber on April 28, 1941, Serial No. 390,690, and entitled "Phonograph apparatus," and assigned to the same assignee as the present invention. It is one of the objects of this invention to provide improved apparatus of this character.

It is preferred to use for the blank on which the record is formed, a thin disc of material which may be readily embossed by the recording stylus. Thus, it is necessary to provide mechanism to cause the recording stylus to be positively traversed across the record surface, as the recording progresses. Due to the shallow depth of such a record groove, it is also desirable to cause the reproducing stylus to be positively traversed across the record surface.

It is another object of this invention to interlink the motion of the reproducer with that of the recorder in a simple and effective manner, and further to provide an improved arrangement for adjusting the relative positions of the recorder and reproducer with respect to the record groove. In this way the reproducer may be so adjusted as to be in position to play back the immediately preceding recorded matter whenever desired, without the necessity of subsequent adjustments.

This invention possesses many other advantages, and has other objects which may be made more easily apparent from a consideration of one embodiment of the invention. For this purpose there is shown a form in the drawings accompanying and forming part of the present specification. This form will now be described in detail, illustrating the general principles of the invention; but it is to be understood that this detailed description is not to be taken in a limiting sense, since the scope of this invention is best defined by the appended claims.

In the drawings:

Figure 1 is a top plan view, partly in section, of a phonograph incorporating the invention;

Fig. 2 is a sectional view as seen on plane 2—2 of Fig. 1;

Fig. 3 is a view similar to Fig. 1, but with the deck and certain other parts broken away to show the operating mechanism;

Fig. 4 is a side elevation partly in section as seen from the right hand side of Fig. 3, and as indicated by arrow 4 in that figure;

Fig. 5 is a detail section as seen on plane 5—5 of Fig. 2;

Fig. 6 is a plan view of the structure of Fig. 5, with the protective cover removed, substantially as seen on plane 6—6 of Fig. 5;

Fig. 7 is a sectional view on an enlarged scale, 10 as seen on plane 7—7 of Fig. 5;

Fig. 8 is a fragmentary detail section as seen on plane 8—8 of Fig. 5;

Figs. 9, 10, 11 and 12 are fragmentary detail sections as seen on the correspondingly numbered 15 planes of Fig. 7;

Fig. 13 is a transverse section as seen on plane 13—13 of Fig. 12; and

Fig. 14 is a detail section as seen on plane 14—14 of Fig. 10.

The phonograph apparatus is provided with a turntable 1 adapted to carry a record receiving blank 2 (Figs. 1, 2 and 3) and supported for rotation about a vertical axis by means of a spindle mechanism 3 (Fig. 2). Rotation is imparted to turntable 1 by means of a floating puck or idler 4 (Figs. 2 and 3), resiliently urged into frictional engagement with lower face of the turntable 1 and the surface of an elongated driving roller 5, driven by any suitable source of power, such as a small electric motor 6 (Fig. 3). Rotation of the turntable 1 serves to drive a feed screw 7 (Fig. 3) through suitable gearing 8, the rotation of the feed screw causing a slidably supported frame or carriage 9 to move transversely with respect to the turntable 1. Frame 9 by means of arm 10 (Figs. 1, 2 and 3) carries the recorder 11, which may be preferably an electrically operated type recording head with a stylus 12 which bears upon the record blank 2. The recorder 11 and frame 9 are so arranged that the stylus 12 moves across the record in a substantially radial direction.

The idler or puck 4 is so carried by frame 9 that it remains in fixed lateral relationship with stylus 12. Thus, as stylus 12 traverses record 2, due to lateral motion of frame 1, the speed of rotation of the record 2 and the turntable 1 progressively changes due to the movement of idler 4 toward or away from the axis of the turntable 1. In this way, a substantially constant linear speed of the record 2 past the recording stylus 12 is provided.

The reproducer 14 (Figs. 1, 2, 5, 6 and 7) may likewise be preferably an electrical type head, arranged for radial movement across the record surface at some convenient angle with the

path of the recorder head 11. The reproducer head 14 is supported by frame 15 (Figs. 6 and 7), its stylus 16 engaging the surface of record 2. Reproducer 14 is connected with frame 9 so that it moves simultaneously with recorder 11, this connecting means being so arranged that the reproducer follows the recorder in the record groove with a small adjustable amount of lag. Means are provided for optionally lifting either stylus out of contact with the record, as well as disconnecting frame 9 from the feed screw, and stopping rotation of the turntable 1.

As clearly shown in Figs. 1, 2 and 3, the entire apparatus is secured to a rectangular deck plate 20, which may be supported in any convenient manner. Secured to plate 20 beneath opposite end edges thereof by any suitable means are frame members 22 and 23 (see particularly Figs. 3 and 4). Tubular members 24, 25 and 26 extend between frames 22 and 23, the ends of these members being secured in the frames 22 and 23 in any convenient manner.

These members 24, 25 and 26 serve to support various parts of the mechanism.

As best shown in Fig. 2, the turntable 1 may be secured to the spindle proper 30 of spindle mechanism 3 as by being attached to a plate 31 on spindle 30 in any convenient manner. Spindle 30 is supported at its lower end on a single ball 34 forming a thrust bearing and resting on an adjustable plug 35 in the bottom of a housing 36. Spindle 30 is radially guided by a long bearing sleeve 37 formed in the top cover 38 of a housing 36. This housing is seen to best advantage in Fig. 2. Housing 36 is secured to tubular members 24 and 25 by means of split arms 39 and 40 (see Fig. 3) through which members 24, 25 respectively pass. Set screws 41 serve to clamp the arms about their respective supports.

The record member 2 may be of the form described in a prior application filed in the name of Frank Rieber, on September 19, 1939, Serial No. 295,613, and entitled "Sound record carrier." Such a record may be very thin, having a thickness of the order of .015".

A pin 42 is provided in plate 31 extending upwardly through a suitable opening in the turntable 1 to engage opening 44 in record 2, for ensuring that the record 2 rotates with turntable 1.

The recorder 11 is of a conventional electrical type and includes a casing 45 (Figs. 1 and 2) enclosing the actuating mechanism from which stylus 12 projects. Casing 45 is suitably secured as by screws 46 in arm 47 which in turn is pivotally carried at 49 by the arm 10 on frame 9 (see Fig. 1).

A bracket 56 in arm 10 rotatably carries a shaft 65 which has a small operating or thumb lever 66 at its outer end. A cam 67 is pinned on shaft 65 and is adapted to engage a push rod 68 pivotally connected as by a clevis 69 to an ear 70 on arm 47.

If it is desired to raise stylus 12 above the record surface, cam 67 is turned approximately 90° clockwise by means of handle 66, bringing the high part of cam 67 into contact with rod 68 and swinging arm 47 upwardly about its pivot 49 in arm 10 and raising recorder 11.

As previously mentioned, arm 10 is carried by the carriage structure 9. Thus the arm 10 includes a vertical column-like portion 90 terminating in a foot 91 which rests on the carriage 9. A long stud 92 passes downwardly

through column 90 and threadedly engages carriage 9, a cap nut 93 serving to secure the arm 10 on the carriage. Suitable dowel pins (not shown) are provided to prevent the arm 10 rotating about the stud 92 as a pivot.

The carriage 9 is of a triangular or A-shaped form as shown in Fig. 3 and is slidably supported at each of its extremities on the tubular members 25, 26.

The mechanism for advancing carriage 9 as the recording progresses will now be described in detail. Due to the thinness of the record 2 which it is intended to use, it is preferable to have the recording proceed from near the center toward the periphery of the record 2 to ensure against buckling (in the direction indicated by arrow 115, Fig. 1).

As clearly shown in Fig. 3, lead screw 7 extends from near the spindle structure 3 to frame 22. One end of the lead screw 7 is rotatably supported in a suitable bushing 116 in frame 22, the other end being supported in a similar bushing 117 in the housing 36.

Mounted on lead screw 7 near one end thereof so as to be disposed within housing 36 is a gear wheel 118 having spiral teeth adapted to engage the teeth of a cooperating spiral pinion 119 secured on spindle 30. Accordingly, the lead screw 7 is driven by the turntable spindle, and the angular motion of screw 7 is at all times proportional to the angular motion of the turntable 1. By appropriate choice of the pitch of the threads on lead screw 7 and of the ratio between gears 118, 119, the pitch of the grooves formed on record 2 may be of any desired value. Further, by altering the direction of rotation of the lead screw 7, or of the screw threads on the lead screw, the recording could be formed from the periphery of the record inwardly.

As previously pointed out, rotation of the lead screw produces a corresponding movement of the recorder 11. This is accomplished by the aid of a feed nut 120 carried by the carriage or frame 9.

The nut 120 has a pair of fragmentary internally threaded and axially spaced bands 121 and 122, joined by a yoke 123. Bands 121 and 122 occupy oppositely disposed angular portions of a complete circumference, so as to engage the threads of lead screw 7 on diametrically opposite portions thereof. In this way a rotation of yoke 123 about an axis 124 radial to screw 7 serves either to engage or disengage the threads of bands 121 and 122 with or from the threads of screw 7.

In order to permit such rotation, as well as to connect the nut 120 operatively to carriage 9 so that movement of the nut 120 will advance the carriage, a shaft 125 is fastened to yoke 123. Shaft 125 is supported for rotation about axis 124 by a guide 126, secured to carriage 9 in any convenient manner.

Shaft 125 is resiliently urged about its axis 124 to move the interrupted bands 121 and 122 into engagement with lead screw 7. This may be accomplished for example by the aid of a tension spring 135, one end of which is secured to crank arm 137, the other end being anchored to a post 136 on carriage 9. When it is desired to disengage the nut 120 from screw 7, the shaft 125 is turned counterclockwise through a small angle, as viewed from the top. The means for accomplishing this will be described hereinafter.

The mechanism for rotating the turntable 1 will now be described (see Figs. 2 and 3). As previously mentioned the source of power for this

rotation may be an electric motor 6 (Fig. 3). The shaft or motor 6 carries a small pulley 140 connected by belt 141 to a large pulley 142 mounted on one end of shaft 143 which shaft carries drum 5. Shaft 143 is rotatably supported in frame 23 by a suitable bushing 144. The other end 155 of shaft 143 is journaled in the bushing 117 supported by housing 36. The lead screw 7 and shaft 143 together with driving roller 5 are coaxial. The idler 4 is in driving relation with roller 5 (which may be of metal) as well as with the underside of table 1. Idler 4 may have a resilient rim 145 of rubber or other suitable material. An opening 146 is formed in plate 20 to permit the idler 4 to engage the underside of table 1.

The idler 4 is freely rotatable on stub shaft 147 which is secured on arm 148, slideable with respect to frame 9. Thus arm 148 is pivoted in an inverted U-shaped link 149 which in turn is pivotally attached to a lug 150 on frame 9 (see Fig. 3). The rear end of bar 148 is slideable between a pair of cylindrical posts 151 and 152, each secured to the top of frame 9 by a screw 153. A bar 154 joints the tops of posts 151, 152. The idler 4 is urged resiliently toward the right, into the driving position, by the aid of a tension spring 156, one end of which is secured to the pivoted link 149, the other end being anchored to a post 157 on carriage 9. When it is desired to disconnect the drive to the table 1 bar 148 is moved toward the left, from the position of Fig. 3.

Convenient means are provided for lifting the recording stylus 12 from the record 2, as well as to stop rotation of the turntable 1, and disengage the feed nut 120 from the feed screw 7. Thus, the position of the recorder as well as the reproducer on the record may be adjusted.

This control mechanism will now be described. As best shown in Figs. 1 and 3, a vertical shaft 160 is rotatably supported within column 90. This shaft carries a crank arm 163, to which is pivotally attached a clevis 164. A connecting rod 165 is in turn pivotally attached at one end to clevis 164 and at the other end to crank 83 which is mounted on the end of the cam shaft 65 (Fig. 1). Thus when crank 83 is rotated by movement of lever 66, rotation is imparted to shaft 160.

When lever 66 is in the forward horizontal position of the drawings, the recorder stylus 12 is in contact with the record, as previously described, and crank 83 is perpendicularly upward with respect to lever 66. When lever 66 is moved through 90° to raise the recorder head, crank 83 by means of the described connections swings shaft 160 in a clockwise direction about its axis. Shaft 160 carries a lever 166 (Fig. 3) near its lower end to which is pivoted one end of a link 167. The other, or left hand end, of link 167 operates a lever 168 pivoted on a post 169 on the top of frame 9. The free end of lever 168 is arranged to cooperate with a stop 170 secured to the top of bar 148. Sufficient clearance must be provided between stop 170 and lever 168 to ensure that the recording stylus 12 is clear of the surface of record 2 before the idler 4 is moved out of driving engagement.

It is necessary that this movement of thumb lever 66 also disengage feed nut 120 from feed screw 7. In order to accomplish this, shaft 160 carries another crank 173 to which one end of a link 174 is connected. The opposite end of link 174 is slidably supported in a bracket 175 carried by frame 9. The free extremity of link 174 is

bent up as indicated by 176 so as to engage and rotate crank 137 in response to outward axial movement of link 174, caused by rotation of shaft 160. Rotation of crank 137 in turn rotates shaft 125 and feed nut 120, causing arms 121, 122 to swing out of engagement with feed screw 7. Thus movement of thumb lever 66 through 90°, first lifts the recording stylus 12 from the record surface, then stops rotation of the turntable 1, and finally frees the nut 120 from the feed screw 7.

The reproducer or playback head 14 is arranged to traverse the record 2 in a direction transverse to the direction of movement of the recorder 11, and as indicated by arrow 181, Fig. 1.

The reproducer 14 may also be of the electrical type, having a stylus 16, which may be permitted at will to rest upon the record 2 by gravity. Reproducer 14 has a rearwardly extending shank 182 (see Figs. 2 and 7) adapted to be secured in a tubular extension 183 (see also Figs. 9 and 10), which extends through and is rotatably supported in block 184. The face of block 184 has a notch 185 extending diametrically of tube 183, adapted to be engaged by a transverse pin 186 projecting from one side only of tube 183. Pins 187, 188 project from this face, being so arranged by engaging pin 186 as to limit movement of tube 183 to 180°.

A counterweight 190 is secured to the rear end of tube 183 and forms a shoulder 191, between which and block 184 a compression spring 192 is accommodated. Spring 192 acts to urge tube 183 axially in block 184, causing pin 186 to engage notch 185. This serves to maintain the stylus 16 in a plane normal to the record surface. If desired, the head 14 may be lifted slightly and together with tube 183 rotated half a turn about the axis of the tube. This turns the head 14 over with the stylus 16 on top, the pin 186 and notch 185 serving to maintain it in this position, when such operations as replacement or repair of parts may be effected.

Block 184 is mounted for universal movement with respect to supporting frame 195 (Figs. 7 and 9), by an inverted T-shaped hanger 196. The vertical leg 197 of this hanger passes through a hole 198 in carriage or frame 195 and is supported therein by a washer 199 and pin 200. The horizontal part 201 of hanger 196 supports block 184 by means of adjustable pintle or bearing screws 202 carried by the block and engaging the ends of part 201. The block 184 and hanger 196 form a freely adjustable universal joint for the reproducer arm assembly, permitting the reproducer stylus 16 to follow any minor vagaries of the record groove.

Carriage 195 is slidably supported on rods 205, 206 of frame 15 (Figs. 5, 6 and 7) for movement parallel to the surface of record 2. These rods are mounted in arms 207, 208 secured to the back frame member 22 and overhanging the deck plate 20. A sheet metal cover plate 209 for this described mechanism is supported on arms 207, 208.

Means are provided to move carriage 195 along its supporting rods 205, 206 to cause reproducer 14 to traverse the record. The specific mechanism for this will be described hereinafter.

To form a convenient means for lifting reproducing stylus 16 from the record 2 when desired, an eccentric 210 is rotatably mounted on carriage 195 (see Figs. 6, 7 and 11). Thus, a short tube 211 is mounted in suitable bores formed in carriage 195, one end of the tube hav-

ing a flange 212 and being partially closed by a wall 213. The eccentric 210 is secured on the other end of tube 211 as by a set screw 215 so as to retain tube 211 on carriage 195. A bar 216 normally rests on the eccentric 210.

A U-shaped strap 217 (Figs. 7, 10 and 14) is pivoted at 218 to carriage 195 and loosely embraces tube 183. The bar 216 is pinned to strap 217 by means of screw 221. Rotation of eccentric 210 from the position of Fig. 7 will swing strap 217 upwardly about its pivot 218, the strap engaging tube 183 and swinging the reproducer upwardly about pivots 202. Since it is necessary to prevent lateral displacement of the reproducer 14 relative to carriage 195 when it is suspended above the record, the lower end of strap 217 is provided with a deep V-notch 220, the sides of which are adapted to engage tube 183 and hold it against sideward movement.

When strap 217 is in its lower position so that the reproducer stylus 16 supports reproducer 14 on the record, the strap is sufficiently below arm 183, to provide clearance between the arm 183 and notch 220, so that the arm and reproducer may have a certain amount of free lateral movement. To provide for accurately adjusting this clearance, the angular position of bar 216 with respect to strap 217 may be adjusted by loosening the screw 221.

For conveniently rotating eccentric 210 to raise or lower reproducer 14, a knob 225 (Fig. 6) is provided on the exterior of cover 209. Knob 225 is mounted on one end of a shaft 226 which is rotatably supported in the adjacent portion of cover 209. Shaft 226 passes through the end wall 213 of tube 211, so as to be splined therein and supported thereby, whereby rotation of the shaft 226 will rotate the tube 211 together with the eccentric 210. For example, shaft 226 may be square for almost its entire length, and wall 213 provided with a corresponding square hole.

The reproducer 14 is made automatically to follow the traversing motion of the recorder 11 by means of a flexible element or cable 230 (see Figs. 3, 4, 5, 6 and 7) to which the reproducer and the recorder are both joined. This element 230 is appropriately guided by suitable pulleys supported on the frame members.

Thus, a guide pulley 231 is rotatably supported near the end of tubular frame member 26 (see Figs. 3 and 4); similar pulleys 235 and 236 are supported near the middle of member 26 by a bracket 237 (see also Fig. 5). The top reach of element 230 passes between pulleys 231 and 235 and is secured to carriage 9 by a suitable clamp 233 carried on member 110, which serves as one of the supporting elements of the carriage. The lower reach of element 230 passes between pulleys 231 and pulleys 236, a slot 234 being provided in member 110 to permit it to move freely with respect to the carriage. Cable 230 passes around pulleys 235 and 236 and upward to similar pulleys 238 and 239 (Figs. 5, 6 and 7), rotatably supported in the end of arm support 208. Element 230 passes from pulley 238 parallel with rod 206 and freely in front of carriage 195 to a pulley 240 mounted in the end of arm 207; thence from pulley 240 along the rear of bar 206 to pulley 239, being secured to carriage 195 in any convenient way. Thus, as frame 9 carries recorder 11 transversely of the record, a movement in the same sense and equal in amount is imparted to reproducer 14.

It may be desirable to vary the distance relative to the record groove by which the repro-

ducer 14 follows the recorder 11. It is possible to make such adjustment by appropriate manipulation of clamp 233, or the means securing cable 230 to carriage 195, but a simpler and more accurate method is desirable. A convenient way in which such lag can be varied will now be described.

By referring to Figs. 6, 7, 12 and 13, it will be seen that a threaded bar 245 is rotatably supported on carriage 195 adjacent cable 230. Bar 245 has a portion 246 of reduced diameter at one end rotatably carried in a suitable opening 247 in one side member 258 of carriage 195. The opposite end of bar 245 has a similar reduced portion 248 rotatably mounted in a bushing 249. Bushing 249 has an outside diameter slightly in excess of the diameter of bar 245 and is secured in a suitable opening 250 in the other side member 259 of carriage 195, in any convenient manner, for example as by a set screw 251. The purpose of bushing 249 is to permit assembly of bar 245 on the carriage 195. Side members 258 and 259 are joined by a sleeve or tubular piece 266 which slidably supports the carriage on bar 206.

A nut 252 threadedly engages bar 245 and has an extension 253 with a horizontal groove 254 for receiving cable 230. Nut 252 may be secured to move with the cable 230 by means of a screw 255 arranged to press a washer 256 against cable 230, the cable thus being clamped between the washer 256 and the bottom of groove 254. Thus, nut 252 is moved by movement of cable 230, and due to the connection between nut 252 and carriage 195 by bar 245, the carriage will be moved by the cable.

Obviously, rotation of bar 245 will cause nut 252 to move relative to carriage 195, which alters the position of carriage 195 with respect to cable 230, and hence with respect to carriage 9. Thus, the position of reproducer 14 with respect to the recorder 11 is altered, varying the amount of lag between the reproducer and recorder with respect to the record groove.

To prevent any rotational movement of nut 252 when bar 245 is rotated, a guide bar 257 slidably supports the nut.

To provide for convenient rotation of the threaded bar 245, a knob 270 adjacent knob 225 is provided. Knob 270 is mounted on a shaft 271, rotatably supported in cover 209 similarly to shaft 226. Shaft 271 passes through bar 245 so as to be supported thereby, and is splined therein, so that the bar may slide along the shaft as the carriage 195 moves. Thus shaft 271 may be square for most of its length, bar 245 being provided with a corresponding square hole 272 for receiving the shaft.

By appropriate setting of the lag of reproducer 14 it is possible to reproduce the immediately preceding recorded matter at any time by simply lifting the recorder 11, and by dropping reproducer 14 to active position. Then by appropriate electrical switching, the reproducer 14 may be placed into electrical operation. During recording the reproducing head 14 may be raised by appropriate manipulation of the knob 225.

It may be required to make it possible to set the reproducer 14 so that it complies with a desired portion of the record disc 2. Logging cards may be used for this purpose, upon which may be indicated the material that is recorded. Thus for example the reproducer carriage 195 may have a projection 260 (Figs. 5, 6 and 7) extending through a slot 261 in the cover member

209. Attached to the projection 260 may be a pointer 262. This pointer is intended to traverse a card 263 (Figs. 1 and 7). This card 263 is shown as provided with graduations 264 cooperating with the pointer 262 and corresponding to accurate time intervals of the record. Opposite these graduations may be appropriate identifying matter to indicate what is recorded adjacent these graduations on the record corresponding to the card in use.

The card 263 may be utilized, during the process of recording, for notation of the recorded material, since the pointer 262 also corresponds to the position of the recorder 11.

The card 263 may be held appropriately in place on cover member 209 (Figs. 1 and 28) as by the aid of a spring pressed button 265.

As previously mentioned, one end of shaft 271 is rotatably supported in a portion of cover 209, and this support also secures the shaft 271 against axial movement. Referring to Fig. 8, it will be seen that the end portion 272 of shaft 271 is of circular cross section. Knob 270 has a bushing 273 secured therein adapted to fit over this circular portion 272 and which extends through a suitable opening 274 in cover 209, thus rotatably supporting the knob 270 and shaft 271. A set screw 275 serves to secure the knob 270 and bushing 273 on shaft 271. Confined between the shoulder on shaft 271 formed where the circular portion 272 meets the square portion of the shaft and the outer face of bushing 273 is a washer 276. This washer 276 cooperates with hub 277 on knob 270 to prevent axial movement of shaft 271. Shaft 226 and knob 225 are arranged in a similar manner.

What is claimed is:

1. In a phonograph, a recorder and a reproducer adapted for cooperation with a record, a pair of guided movable carriages respectively carrying the recorder and the reproducer, a flexible element, means connecting said carriages to said element for simultaneous movement, one of said connecting means including a pair of threaded members respectively carried by said element and the associated carriage, and means for rotating one of said members, whereby the position of said carriage with respect to the element may be altered.

2. In a phonograph, a recorder and a reproducer adapted for cooperation with a record, a pair of movable carriages respectively carrying the recorder and the reproducer, guide means for each of said carriages, said guide for the recorder being arranged to guide the movement of the recorder carriage at an angle with the movement of the reproducer carriage, means to positively move one of said carriages, a flexible element joining the carriages whereby movement of said one carriage is imparted to the other carriage, and means whereby the relative positions of said carriages with respect to said element may be altered, comprising a threaded member carried by one carriage and serving to connect said carriage with said element.

3. In a phonograph including a sound head adapted for cooperation with a record, a guided movable carriage for said head, a flexible element for moving said carriage having at least a portion extending in the direction of movement of the carriage, a pair of threaded members respectively attached to said carriage and said element, the axis of said members extending generally in said direction of movement,

and means for causing relative rotation between the threaded members, whereby the carriage is moved along the element.

4. In a phonograph including a sound head adapted for cooperation with a record, a guided movable carriage for said head, a flexible element for moving said carriage having at least a portion extending in the direction of movement of the carriage, said carriage including a pair of spaced side members, a threaded bar having pintles at opposite ends for rotatably supporting it in said side members, a nut secured to said flexible element and threadedly engaging said bar, and means to rotate said bar.

5. In a phonograph, a frame having guides for supporting and guiding a movable carriage carrying a sound head adapted for cooperation with a record, a flexible element having at least a portion extending parallel with said guides, adjustable means connecting said carriage and said element for simultaneous movement, said means including a rotatable member for altering the relative positions of said carriage and said element upon rotation, a shaft splined in said rotatable member, and means forming a bearing in the frame for one end of said shaft.

6. In a phonograph, means forming a guide for supporting a movable carriage adapted to carry a sound head for cooperation with a record, said means including a bar, said carriage having spaced side members joined by a sleeve slidable along said bar, a flexible element parallel with said bar passing through side members and closely spaced from said sleeve, a threaded bar extending between the side members and rotatably supported thereby, a nut threadedly engaging said bar, means securing said nut to the flexible element, and a guide for the nut.

7. In a phonograph, a sound head, a guided movable carriage, a shank on the sound head, and means supporting the shank on said carriage, said means permitting universal movement between the shank and the carriage.

8. In a phonograph, a sound head adapted for cooperation with a record, a guided movable carriage, a shank on the sound head, a block rotatably supporting said shank, means on said carriage supporting said head for movement in a plane normal to the record, said shank and said block having cooperating detent means for positioning the sound head for use with the record.

9. In a phonograph, a sound head adapted for cooperation with a record, a guided movable carriage, a member supported on the carriage for movement about an axis, a block supported by said member for movement about an axis perpendicular to the first mentioned axis, means supporting the sound head in said block, and a counterweight for said sound head.

10. In a phonograph, a sound head adapted for cooperation with a record, a guided movable carriage, a member supported on the carriage for movement about an axis, a block supported by said member for movement about an axis perpendicular to the first mentioned axis, means supporting the sound head in said block, including a shank, a U-shaped strap pivotally supported at its upper end on said carriage and embracing the shank, centering means for the shank carried by said strap, and means on said carriage to swing the strap about its pivot to engage the shank and lift the sound head.

11. In a phonograph, a sound head adapted for cooperation with a record, a guided movable carriage, a block supported on the carriage for

universal movement with respect thereto, means rotatably supporting the sound head in said block, and detent means limiting the rotation of the sound head to approximately 180°.

12. In a phonograph, a sound head adapted for cooperation with a record, a guided movable carriage, a block supported on the carriage, means forming a shank on the sound head, said block

supporting the shank for axial as well as rotational movement, means forming a projection on said shank, means resiliently urging said projection against the face of the block, there being angularly spaced depressions formed in the face of the block for engaging said projection and restricting rotation of the shank.

GEORGE P. BRUBAKER.
